UNITED STATES PATENT OFFICE.

ERNEST SALISBURY, OF ASPEN, COLORADO, ASSIGNOR OF ONE-HALF TO GEORGE RUNTZ, OF ASPEN, COLORADO.

ELECTRICAL GATE-OPERATING MEANS FOR RAILROADS.

1,101,715.

Specification of Letters Patent. Patented June 30, 1914.

Application filed December 13, 1913. Serial No. 806,537.

To all whom it may concern:

Be it known that I, ERNEST SALISBURY, a citizen of the United States, residing at Aspen, in the county of Pitkin and State of Colorado, have invented certain new and useful Improvements in Electrical Gate-Operating Means for Railroads, of which the following is a specification, reference being had to the accompanying drawings.

This invention relates to improved railway gate operating mechanism and has for its primary object to produce a simple, efficient and inexpensive apparatus for the above purpose which is operated by the closing of an electric circuit when the train reaches a predetermined distance from the crossing whereby the gate arms are disposed in horizontal position across the road or street.

My invention has for a further and more specific object to provide a motor operated means for the gate arms, a circuit for the motor, means arranged in the track and engaged by a contact member carried by the train whereby the circuit is closed, electromagnets for each of the gate arms connected in series and arranged in said circuit to retain the gate arms in their lowered position, and a switch actuated by one of the gate arms to cut the motor out of the circuit after the arms have been lowered.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a top plan view showing my improved operating mechanism for the crossing; Fig. 2 is an elevation of said mechanism; Fig. 3 is a section taken on the line 3—3 of Fig. 1; Fig. 4 is a section taken on the line 4—4 of Fig. 2; Fig. 5 is a diagrammatic view illustrating the operating circuit.

Referring in detail to the drawings, 5 designates a shaft which is journaled at its ends in suitable bearings 6 arranged in a housing or casing 7 which is mounted upon a suitable foundation beneath the railroad track indicated at 8. Upon each end of this

shaft a sprocket 9 is secured. In bearings 10 arranged within the casing or housing 7, the shafts 11 are mounted. Each of these shafts has a sprocket 12 fixed upon one end which is driven by a chain 12' from the sprocket 9 on the shaft 5. Upon each shaft 11 between its supporting bearings 10, a gate arm 13 is secured by means of a suitable set screw 14.

15 designates an electric motor of any preferred type the shaft of which is provided with a pinion 16 engaging one of the chains 12'.

Magnets 18 are arranged adjacent each of the gate arms 13 upon suitable supports 19 and are adapted to retain the gate arms in their lowered position by magnetic attraction. These magnets are connected in series by means of the wire 20 and are included in the operating circuit as will be later described.

Upon the upper end of a suitable post or standard 21, an electric bell 22 is arranged, and an electric light bulb 23 is also mounted upon this pole so that a visual as well as the audible signal may be given.

Between the rails of the track 8, a third rail 24 is arranged. This rail includes comparatively short end sections 25 which are spaced from the opposed ends of the longer intermediate section thereby providing gaps 26. The locomotive indicated at 27 is provided with a contact roller 28 which is adapted to engage with the third rail sections, said roller being mounted in the metal frame of the engine or otherwise mounted so as to act as an electrical conductor to the drive wheels.

The operating circuit is diagrammatically illustrated in Fig. 5 of the drawings and includes a battery, generator or other suitable source of electric current indicated at 29 and to one terminal of said battery, a wire 30 is connected; the other end of this wire being connected to one of the track rails 8. A wire 31 leads from the other terminal of the battery 29 to one side of the motor 15. In this circuit wire 31, a switch is arranged, said switch including a movable blade or knife 32 and a stationary contact member 33. The knife blade is normally disposed by gravity in engagement with the stationary contact member so as to close the circuit through the wire 31. A wire 34 is connected to the other side of 110

the motor and to the intermediate section of the third rail 24. This wire is also connected by the wire 35 to one set of magnets 18, while the other set of magnets is connected by the wire 36 to the wire 31. The end sections 25 of the third rail are connected by a conducting wire 37 and a wire 38 is joined to the wire 37 and extends to the lamp 23, the other wire 39 from the lamp being joined to the wire 31. The wires 40 and 41 from the battery of the bell 22 are joined to the wires 38 and 39 respectively.

It will be noted that the gate arms 13 are mounted upon the shafts 11 adjacent one of their ends, and said ends are enlarged or weighted as indicated at 42, so that the longer portions of the arms extending upon one side of the shaft are normally held by gravity in an elevated position. It is further to be noted that the movable knife or blade 32 of the switch extends over the weighted end of one of the gate arms.

Having above described the construction and arrangement of the several parts of the mechanism, and the circuit connections therefor, the operation of the invention will be understood as follows: The circuit connections are such that the device will be properly operated when the train approaches the crossing from either direction. Assuming that the train is moving in the direction indicated by the arrow in Fig. 5 of the drawings, when the wheel or roller 28 carried by the locomotive strikes the end section 25 of the third rail, the circuit will be closed from the battery 29, through wire 30 and the track rail, through the frame of the locomotive and the roller 28, then through the third rail section and wire 37, to the lamp and bell through the wires 38 and 39, 40 and 41 then through wire 31 to which the wire 39 is joined, back to the battery. Thus it will be seen that the bell is rung and the lamp lighted while the contact wheel 28 of the locomotive is disposed upon the end sections of the third rail. When this rail moves into the gap 26, the lamp and bell circuit is broken and the wheel then engages upon the main central section of the third rail. A circuit is now closed from the battery through wire 31 and the switch through the motor 15, then through wire 34 to the third rail, through contact wheel 28 and the drive wheel of the locomotive and one of the track rails through the wire 30 and thence back to the battery 29. Thus the motor will be operated and the gate arms lowered across the road crossing indicated at C. Simultaneously with the closing of the motor circuit, the magnets 18 are energized by the connection of said magnets by means of the wires 35 and 36 to the wires 34 and 31 respectively, said magnets themselves being connected in series by the wire 20. These

magnets act by magnetic attraction to hold the gate arms in their lowered positions after one of said arms has engaged the movable blade or knife 32 of the switch and moved the same from engagement with the contact plate 33 which breaks the motor circuit, so that the operation of the motor is discontinued. When the train has moved to the opposite side of the grade crossing and the contact wheel 28 moves off of the intermediate section of the third rail 24, the circuit for the electromagnets is also broken and the gate arms then return to their normal positions by gravity. It is of course understood that in a double track system, where the trains would only move in one direction upon each track, one of the end sections 25 of the third rail would be dispensed with, and the wire 37 connected directly to the lamp.

From the foregoing description taken in connection with the accompanying drawings, it is thought that the construction and operation of my invention will be clearly and fully understood. The apparatus is entirely automatic in its operation and requires no care or attention upon the part of the train crew and obviates the necessity of employing an attendant to be stationed at the road crossing. The mechanism as a whole is also simple in its construction and may be installed in condition for use at very small cost and without necessitating any alterations in the ordinary track construction.

While I have described the preferred construction and arrangements of the several parts of my invention, it will be understood that the invention is susceptible of considerable modification therein and I therefore reserve the right to resort to all such legitimate changes as may be fairly embodied within the spirit and scope of the invention, as claimed.

Having thus described the invention, what is claimed is:

1. In an apparatus of the character described, movable gate arms arranged upon opposite sides of a railroad track, said arms being normally held in their elevated positions by gravity, electrical operating means for said arms including a motor and circuit therefor, a switch arranged in said circuit having a movable element normally held by gravity in its closed position, said element being adapted to be engaged by one of the gate arms in its movement to its closed position to open the circuit and stop the motor, a third rail arranged between the track rails and also included in the motor circuit, electromagnets for each of said arms cooperating directly therewith when the arms are in their lowered positions to maintain the arms in such positions after the operating circuit has been opened, and direct electrical connection

tions between said magnets and the operating circuit.

2. In an apparatus of the character described, movable gate arms arranged upon 5 opposite sides of a railroad track, said arms being normally held in their elevated positions by gravity, electrical operating means for said arms, a circuit therefor, a switch arranged in said circuit including a movable 10 element adapted to be engaged by one of the gate arms and moved to its open position, a third rail arranged between the track rails, a circuit wire connecting said rail to the operating means, electromagnets for each of 15 said arms to hold the same in their lowered positions after the switch has been opened, and direct electrical connections between said magnets and the operating circuit.
3. In an apparatus of the character de- 20 scribed, movable gate arms arranged upon opposite sides of a railroad track, said arms being normally held by gravity in their ele- vated positions, electrical operating means for said arms, a circuit therefor, said circuit including a source of current supply, a cir- 25

cuit wire extending from the supply source to the operating means, a switch interposed in said circuit wire including a movable element disposed in the path of movement of one end of the gate arm and moved thereby 30 to its open position, a wire extending from the current supply source to one of the track rails, a third rail arranged in the track, a circuit wire connecting the third rail to the operating means, a set of electromagnets for 35 each of the gate arms to hold the same in their lowered positions, said magnets being connected in series, said third rail being adapted for engagement by circuit closing means carried by the locomotive, and con- 40 ducting wires connecting the respective sets of electromagnets to the circuit wires leading to and from the operating means for the gate arms.

In testimony whereof I hereunto affix my 45 signature in the presence of two witnesses.

ERNEST SALISBURY.
